UNITED STATES PATENT OFFICE.

JOHANN HEINRICH SPOERL, OF DÜSSELDORF, GERMANY, ASSIGNOR TO
MORIZ & KUMMER, OF BERLIN, GERMANY.

APPARATUS FOR CUTTING AND FOLDING TOILET-PAPERS.

No. 839,521.

Specification of Letters Patent.

Patented Dec. 25, 1906.

Application filed April 18, 1905. Serial No. 256,275.

To all whom it may concern:

Be it known that I, JOHANN HEINRICH SPOERL, engineer, a subject of the German Emperor, residing in Düsseldorf, in the Kingdom of Prussia, Germany, have invented certain new and useful Improvements in Apparatus for Cutting and Folding Toilet-Papers, of which the following is a specification.

The present invention relates to a machine by means of which two endless webs of paper are alternately cut up into definite lengths, folded into one another, and ranged in layers on a table, as in the case of toilet-papers.

One embodiment of the present invention is illustrated in the accompanying drawings, in which—

Figure 1 is a part-sectional side elevation of the machine; Fig. 2, a longitudinal section on the line $x x$ of Fig. 1, in which the right half of the machine is considered turned round to the right; Fig. 3, an enlarged diagrammatic representation of parts of Fig. 1, in which all the cylinders are shown turned through one hundred and eighty degrees, the machine-frame being omitted. Fig. 4 shows a pile of papers which have been cut and folded into one another, the places where the separate portions of the two webs of paper have been cut being rendered particularly conspicuous. Fig. 5 shows a plan view of the table and the flexible weight-lever mechanism, and Fig. 6 shows a side elevation of the mechanism illustrated in Fig. 5.

The operative cycle of the machine is as follows: The cylinders $a a'$ and $b b'$ are connected together by means of the toothed wheels $q q'$. The cylinders $a a'$ are provided with the grooves $f f'$, in which during the process of cutting the cutting-knives $g g'$, secured on the cylinders $b b'$, engage. The position of these cutting-knives $g g'$ and the position of the grooves $f f'$ on the cylinders $a a'$ for receiving them must in each of the two cases be displaced exactly through one hundred and eighty degrees with regard to one another, so that the place where the paper-web p is cut is always situated exactly centrally between two places where the paper-web p' is cut. The cylinders $a a'$ are provided with recesses $c c'$, produced by turning out the cylinders eccentrically, and each of the latter are also provided with two rows of points or spikes $e e'$, which in the case of both cylinders are likewise displaced through one hundred and eighty degrees with regard to

one another, so that the cut paper-webs are always pricked through on the cylinder a or a' at the cut places and are carried to the right or to the left, Figs. 1 and 3. The points $e e'$ are so arranged that upon the rotation of the rolls the points e will register with the grooves f in the roll a' and the points e' on the roll a will register with the groove f in the roll a . By this means the points will be protected from injury. The proper folding and piling up or superposing of the paper-webs laid the one in the other are now effected by means of the strippers or grippers $d d'$, which are alternately and in opposite directions moved up and down by means of the system consisting of the connecting-rod h , lever-arm i , lever-arm k , connecting-rod l , and arm m . These strippers are so set that in the raised position (Fig. 3 on the left) they are received in the recesses $c c'$ in the cylinders, whereas during their alternating descent they strip off the paper from the points $e e'$. By this means the desired fold is simultaneously formed, which fold is still further intensified by the pressure of the strippers $d d'$ on the superposed pile of papers. In order to regulate the steady growth of the pile of paper and to keep the same always at the same height under the strippers, the table n must be movable and must be balanced by springs or weights, so that it can move downward according to requirement.

In Figs. 5 and 6 the details of construction of a flexible table for receiving a pile of material is illustrated, and in accordance with the construction disclosed herein a table-board n rests between the standards of the machine and is supported on four arms r , carrying rolls s , and each of which arms is supported by a pair of links $t t'$, pivoted to it and the standard. The links t are shown continued into the arms or levers t'' , which are provided with slots w . These levers t'' at each end of the machine are connected by and carry a rod u , which is adjustable in said slots w . Each of the rods u carries a weight v . By this means the vertical position of the table may be regulated and adjustment may be had between the respective ends of the table, as occasion may demand.

What I claim as my invention, and desire to secure by Letters Patent, is—

1. The combination of a pair of rotatable cylinders adapted to seize two webs of paper and draw the same between them; one web

- passing round one cylinder and the other web round the other cylinder, and each web being transversely cut into separate portions at uniform intervals, the cuts on one web lying midway between those on the other web; 5 a row of spikes on each cylinder, the row on one cylinder being dodged relatively to the row on the other, whereby portions of the two webs may be carried partially around 10 the periphery of one and then another portion partially around the periphery of the other cylinder, and means for stripping the webs from the cylinders and laying the same in a pile.
- 15 2. The combination with a pair of coöperating rotatable cylinders adapted to draw between them two webs of paper, of two rolls one coöperating with each of the said cylinders, each roll and its coöperating cylinder 20 being adapted to feed one of the webs of paper between them, a knife on each roll, a row of spikes on each cylinder whereby portions of the two webs are carried alternately in folds 25 partially around the periphery of the respective cylinders, and means for stripping the webs from the cylinders and laying the same in a pile.
3. The combination with a pair of coöperating rotatable cylinders adapted to draw 30 between them two webs of paper, of two rolls one coöperating with each of the said cylinders, each roll and its coöperating cylinder being adapted to feed one of the webs of paper between them, a knife on each roll, one 35 knife being so arranged with regard to the other that the cuts on one web come to lie midway between those on the other, a row of spikes on each cylinder whereby portions of the two webs are carried alternately in folds 40 partially around the periphery of the respective cylinders, and means for stripping the webs from the cylinders and laying the same in a pile.
4. The combination with a pair of coöperating rotatable cylinders adapted to draw 45 between them two webs of paper, of two rolls coöperating with each of the said cylinders, each roll and its coöperating cylinder being adapted to feed one of the webs of paper between them, a knife on each roll, one 50 knife being so arranged with regard to the other that the cuts on one web come to lie midway between those on the other, a row of spikes on each cylinder, the spikes on one 55 cylinder being adapted to engage the web fed by the other cylinder near the places where it is cut, whereby portions of the two webs are carried alternately in folds partially around the periphery of the respective cylinders, and means for stripping the webs from the cylinders and laying the same in a pile.
5. The combination with a pair of coöperating rotatable cylinders adapted to draw 60 between them two webs of paper, of two rolls one coöperating with each of the said cylinders, each roll and its coöperating cylinder being adapted to feed one of the webs of paper between them, a knife on each roll, one 65 knife being so arranged with regard to the other that the cuts on one web come to lie midway between those on the other, a row of spikes on each cylinder the spikes on one cylinder being adapted to engage the web fed by the other cylinder near the places where it is cut, whereby portions of the two webs 70 are carried alternately in folds partially around the periphery of the respective cylinders, a table whereon such portions are piled, a number of recesses in each cylinder, arms adapted to enter such recesses and upon 75 movement of the same toward the table to strip the paper from the spikes, and means controlled by the rotation of the cylinders to alternately actuate said strippers.
6. The combination with a pair of coöperating rotatable cylinders adapted to draw 80 between them two webs of paper, of two rolls one coöperating with each of the said cylinders, each roll and its coöperating cylinder being adapted to feed one of the webs of paper between them, a knife on each roll, one 85 knife being so arranged with regard to the other that the cuts on one web come to lie midway between those on the other, a row of spikes on each cylinder the spikes on one cylinder being adapted to engage the web fed by the other cylinder near the places where it is cut, whereby portions of the two webs 90 are carried alternately in folds partially around the periphery of the respective cylinders, a 95 movable balanced table whereon such portions are piled, a number of recesses in each cylinder, arms adapted to enter such recesses and upon movement of the same toward the table to strip the paper from the spikes, and means controlled by the rotation of the cylinders to alternately actuate said strippers.
7. In an apparatus of the character described, the combination with two rolls, of means for feeding sheets or units from opposite directions down between the rolls and so timing the feed as to compel the sheets to overlap, and means for folding and interfolding the sheets or units as they pass between and from the rolls.
- In witness whereof I have hereunto signed my name, this 4th day of April, 1905, in the presence of two subscribing witnesses.
